UNITED STATES PATENT OFFICE

HOWARD SUTLIFF, OF LOS ANGELES, CALIFORNIA

DESIGN FOR A DISPLAY DEVICE

Application filed October 24, 1931. Serial No. 41,514. Term of patent 7 years.

To all whom it may concern:

Be it known that I, HOWARD SUTLIFF, a citizen of the United States, residing at Los Angeles, in the county of Los Angeles and State of California, have invented a new, original, and ornamental Design for a Display Device, of which the following is a specification, reference being had to the accompanying drawings, forming a part thereof.

Figure 1 is a top view of a display device, showing my new design.

Fig. 2 is a side elevation of the same as viewed from the right, looking left in Fig. 3.

Fig. 3 is a front elevation of the same.

I claim:

The ornamental design for a display device as shown.

Signed at Los Angeles, in the county of Los Angeles and State of California, this 20th day of October, 1931.

HOWARD SUTLIFF.
